(57) **CLAIM**

The ornamental design for a radar shaped antenna, as shown and described.

DESCRIPTION

FIG. 1 is an upper perspective view of a radar shaped antenna showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIGS. 8 and 9 are perspective views thereof, illustrating rotational movement of the dish of the radar shaped antenna.
